AUTOMOBILE LOCKING MECHANISM

Thomas F. Cullinan, Johnson City, Tenn.

Application March 2, 1933. Serial No. 659,357

10 Claims. (Cl. 251—6)

My invention relates to improvements in automobile motor locking mechanism, and one object of my invention is the provision of a locking mechanism which will absolutely guard the motor vehicle against theft or unlawful use.

Another object of my invention is the provision of a locking mechanism which may be adapted and applied as a replacement to motors now in general use or at the time of their manufacture or as circumstances demand.

Another object of my invention is the provision of a locking mechanism of the character described which will provide the maximum of security against automobile theft. And to provide a device that cannot be unlocked by the cutting or forcibly breaking away of connection of its members.

Another object of my invention is the provision of a locking mechanism which will comprise few working parts to insure simplicity and durability and to insure a long life for the mechanism.

Another object of my invention is the provision of a locking mechanism of the character described which may be manufactured at a comparatively small cost and with its many advantages considered insure the mechanism being highly desirable, efficient and practically theft-proof.

With these objects in view, my invention consists of a locking mechanism of the character and for the purposes described embodying novel features of construction and combination of parts, substantially as described and claimed and as shown in the accompanying drawings, in which:

Figure 1 represents a view in elevation of my locking mechanism applied in proper relation with reference to the dash or instrument board, carburetor and manifold.

Figure 2 represents a view partly in elevation and partly in section on an enlarged scale of the valve operating and control mechanism which is mounted on the dash-board, and showing in dotted lines the key and key operating member in the position they assume when the valve is open.

Figure 3 represents a perspective view of the element in which the key operated member is mounted and which also forms a guide or bearing for the valve operating means.

Figure 4 represents a sectional view taken on line 4—4 of Figure 1.

Figure 5 represents a sectional view taken on line 5—5 of Figure 4.

Figure 6 represents a sectional view taken on line 6—6 of Figure 4, and

Figure 7 represents a sectional view taken on line 7—7 of Figure 4.

Referring by numerals to the drawings, in which the same numbers of reference denote like parts in all the views of the drawings:

The numeral 1 designates the motor, 2 designates the manifold, 3 the dash or instrument board, 4 the carburetor and 5 the valve mounting or block, which is secured in place by means of the nut and bolt securing means 6, which securing means are provided with locking means 7, as shown clearly in Figure 5, which prevent removal of the lock by securing means 6.

The valve mounting or block is provided with the opening 8, and with the offset or extension 9, formed with a chamber 10, and in the opening 8 is journaled the shaft 11, which has one end 12 passing through the wall of the mounting and into said chamber 10, and this extended end of the shaft carries a pin 13, which fits in a slot 14, in the ferrule 15, which ferrule fits in and is secured in proper place by means of the ring 16, retained in place by the fastening 17, and such ring serves as a guide and bearing for said ferrule.

The construction described is shown most clearly Figures 4 and 7, and the said ring is formed with a socket 18, which is adapted to be uncovered or exposed under wanted condition, allowing opening 19 in the ferrule to register with the said opening or socket 18, when the spring locking pin 20 will pass through said opening 19 and seat in the socket 18, which action locks the parts and precludes turning of the shaft 11.

The butterfly valve 21 is provided with a casing or sleeve 22 which fits around the portion of shaft 11, which lies in the valve opening, and through the center of said sleeve projects the bearing lug 23, which is formed with the bifurcated upper end 24, in which it is pivoted at 25, the inner end of arm 26, which when the valve is entirely closed, as shown in Figure 5, has the free end 27, fit in the socket 28, in the wall of the valve block holding the valve fast and to retain the arm or latch 100 in place the flat spring 29 is provided.

It will thus be seen that both the sleeve and the shaft through their connections and relations are capable of a partial rotary movement, and that the lug 23, passes through an opening in the sleeve which opening is of sufficient size to allow the proper movement of the shaft to project and withdraw the latch end 27, from the recess or socket 28, and this particular feature is one of the most important and novel of my invention.

The purpose of arm 26 entering into the valve block is to retain butterfly valve in locked position, even though the carburetor being removed the valve cannot be forced open from the underneath or carburetor side.

From the construction described it will be apparent that the butterfly valve is mounted on the shaft and is rotated by the movement of said shaft into locked and closed position, and is shown in Figures 5, 6 and 7. The wall of the valve block is provided with a pair of openings 29, which lead to the outer air and which, when the valve is fully open, will allow a small amount of air to enter into block positively disrupting the gasoline mixture from carburetor. This is found absolutely necessary under this type of locking conditions to effect the absolute positiveness of a device of this kind.

These openings or vents are covered and uncovered by the shutter device 30, on the extended end of shaft 11, as shown clearly in Figures 4, 5, 6 and 7, which forms a most scientific as well as mechanical feature of my invention.

To the dash or instrument board is rigidly and reliably secured by means of the lug 31, and lock bolt fastening 32, the tubular member 33, to the lower end of which is fitted the cap 34, formed with an opening 35, and fitted in this cap opening and the opening 36, of the ring 37, secured by fastening 38, are the ends of the protecting covering or tube 39, and within this tube and passing throughout its length is the torsional cable or connection 40, and one end of this cable, or, rather, its upper end, is secured to the cylindrical head 41, while the other or lower end 42 is secured to the upper end 43 of the ferrule or cap, and thus movement of the said head 41 and ferrule 15 is effected through rotation of said cable, as will presently appear.

40 The tubular head 41, adapted to turn in the guide lower portion 44, of the sleeve member 45, and is formed on the worm or spiral stub 46 which is enclosed by the tube 47, formed with the lip 48, which fits into said worm groove, and the tube 45 is formed on the rotatable key operated member 49, which is moved in and out by movement of the key, and such movement naturally releases lock plunger, then impressed spring pushing lock forward gives the spiral or worm a turn which imparts a rotary movement to the torsional cable which moves the valve to the desired position.

The key operated member is guided in the sleeve by means of the pin 51 and slot 51', in the sleeve and the sleeve is also provided with a series of graduated openings 52, which receive the stud 53, on the member and thus holds the member at different points to open the valve to varying degrees or to entirely close and lock the valve according to requirements.

60 The key operated member is held to its proper position by the stud 53 and is actuated to its unlocked position by the expansion of coiled spring 54. The ferrule 15 is also retained in proper relation to other parts by means of the coiled spring 55.

70 From the foregoing description taken in connection with the drawings the operation of my locking mechanism will be readily understood and its many important advantages will be fully appreciated. It will be noted through the action of the key operating member on the dash-board that the valve may be operated and controlled gradually, allowing some power to escape into cylinders that the car may be moved under garage re-

quirements, or that valve can be fully closed and absolutely locked against theft.

It will also be noted that the valve may be entirely closed, and when in locked position in the event of the cable connection being cut the 80 ferrule and connected parts operate to lock the valve in shut position.

It will be noted that if the cable or torsional connection is forcibly severed or broken away the ferrule and connected parts are constructed 85 so that the valve will always remain in locked position.

It will be noted that my locking mechanism can be readily installed in motor cars in general use at a comparatively low cost, or as a replacement lock on all types of cars, either now or at 90 time of their manufacture, and that the locking mechanism will commend itself as useful, efficient and practical from every point of view.

It will be noted that the butterfly valve and 95 the means for locking the valve in the mounting are operated from the dash board and through the operation and control of the key operated mechanism and thus a co-action or co-operation of the said mechanisms is provided, 100 which is a most important feature of this invention.

I claim:

1. A motor lock of the character described, comprising a valve mounting adapted to be arranged 105 between a manifold and a carburetor, a butterfly valve arranged in said mounting, a shaft bearing in said valve, a latch carried by said shaft, a recess in the wall of the mounting to be engaged by said latch, and means for operating the 110 valve and shaft.

2. A motor lock of the character described, comprising a valve mounting adapted to be arranged between a manifold and a carburetor and provided with a recess in its wall, a butterfly 115 valve arranged in said mounting, a partially rotatable shaft bearing in said valve, a lug projecting from said shaft, a latch having one end pivoted to said lug and its other end adapted to engage said recess in the wall of the mounting, 120 a spring acting to hold said latch in proper position and means for imparting movement to the shaft and latch.

3. A motor lock of the character described, comprising a valve mounting adapted to be arranged between a manifold and a carburetor, a butterfly valve arranged in said mounting and having a sleeve, a shaft bearing in and partially 125 rotatable in said sleeve, a recess in the wall of said mounting, a latch carried by the shaft and adapted to engage said recess, and means for operating the valve and shaft.

4. A motor lock of the character described, comprising a valve mounting adapted to be arranged between a manifold and a carburetor, a butterfly valve arranged in said mounting, a shaft bearing in said valve and having an extended portion, air passages in said mounting, 135 a shutter on the extended end of said shaft for coating with said air passages, a latch carried 140 by said shaft to lock the valve in closed position, and means for operating said valve, shaft and shutter.

5. A motor lock of the character described, comprising a valve mounting adapted to be arranged 145 between a manifold and a carburetor, a butterfly valve arranged in said mounting and provided with a sleeve, a shaft bearing in said sleeve, a latch projecting from the shaft and serving to retain the valve in closed position, 150

- a torsional connection leading from said shaft, and operating means associated with said torsional connection. 80
6. A motor lock of the character described, comprising a valve mounting adapted to be arranged between a manifold and a carburetor, a recess and air passages suitably located in the wall of the mounting, a butterfly valve arranged in said mounting, a shaft bearing in said valve, a shutter carried by said shaft and coacting with said air passages, a lug projecting from said shaft, a spring latch carried by the shaft and adapted to engage the recess in the wall of the mounting to retain the valve in closed position, and a torsional connection leading from said shaft for transmitting movement to the valve and shaft. 85
7. A motor lock of the character described, comprising a valve mounting adapted to be arranged between a manifold and a carburetor, a butterfly valve arranged in said mounting, a sleeve formed on said valve, a recess and air passages suitably disposed in the wall of said mounting, a shaft bearing in the sleeve of the valve and formed with an extension, a shutter on the extension of the shaft for coaction with said air passages, a latch carried by the shaft for engaging said recess to hold the valve in closed position, a ferrule on the extended end of said shaft having a sliding movement, and means leading from said ferrule for operating the valve, shaft and shutter. 90
8. A motor lock of the character described, comprising a valve mounting adapted to be arranged between a manifold and a carburetor, an extension projecting from said mounting and providing a chamber, a butterfly valve arranged in said mounting and having a sleeve, a shaft bearing in said sleeve and having one end pro- 95
- jected into said chamber of the extension of the mounting, a recess in the wall of the mounting, a latch element on said shaft for engagement with said recess, a ferrule slidably connected with the extended end of said shaft, and operating means leading from said ferrule. 100
9. A motor lock of the character described, comprising a valve mounting adapted to be arranged between a manifold and a carburetor, a recess in the wall of said mounting, a butterfly valve arranged in said mounting, a shaft bearing in said valve and having an extended end, a latch on said shaft for engagement with said recess in the wall of the mounting, a ferrule fitting on the extended end of the shaft and provided with a slot to allow sliding movement, a guide having a pin arranged in said slot, a spring for holding the ferrule in proper position, and torsional operating means leading from said ferrule. 105
10. A motor lock of the character described, comprising a valve mounting adapted to be arranged between a manifold and a carburetor and having a recess and air passages in its wall in proper location, a butterfly valve arranged in said mounting, a shaft bearing in and having partial rotation in said valve and having an extended end, a latch element carried by said shaft for engagement with said recess in the wall of the mounting, a shutter on the extended end of said shaft for coacting with said air passages of the mounting, a ferrule slidably fitted on the extended end of the shaft, a guide for said ferrule, a spring to retain the ferrule in proper relation and operating means leading from said ferrule for imparting partial rotation to the shaft and valve. 110
